UNITED STATES PATENT OFFICE.

LEONARD DOTZER, OF NEW YORK, N. Y., ASSIGNOR TO WALLACE T. JONES, JR., OF BROOKLYN, NEW YORK.

STONE-DRESSING MACHINE.

Application filed June 20, 1921. Serial No. 478,810.

To all whom it may concern:

Be it known that I, LEONARD DOTZER, a citizen of the United States, and a resident of New York, in the county of New York 5 and State of New York, have invented a certain new and useful Stone-Dressing Machine, of which the following is a description.

My invention relates to machines for 10 what is commonly known as "dressing" mill stones, and is adapted to dress, in accordance with the particular requirements thereof, the stones of mills used in grinding or pulverizing material of any kind, such, 15 for example, as cocoa beans, pigments, antimony, copper-scale, grain, cement, ores, inks, etc.

The dressing of a stone comprises the cutting of grooves or "cracks" in its grinding 20 surface, and generally includes, also, the cutting of the larger grooves known as "fours" and the facing of the surface of the stone. Heretofore this has commonly been done manually, by skilled workmen 25 using a chisel and hammer or a pneumatic chisel. The dressing of stones in this way is, of course, a slow and expensive process, and often the results are unsatisfactory due to the unavoidable chipping of the stone and 30 beveling of the cracks.

It has heretofore been proposed to employ in stone cracking, power operated emery wheels driven by a flexible shaft, but so far as I am aware attempts thus to make the 35 work of cracking the stone less laborious have been unsuccessful.

The general object of my present invention is to provide a machine which will dress stones rapidly, efficiently and automatically, 40 and which may be adjusted to cut cracks of any desired character corresponding with the nature of the work for which the stones are intended, and also may be used properly to true the face of the stone.

With this and other objects in view, which 45 will appear more fully hereinafter, my invention consists in the novel machine, parts and combinations of parts described herein and more particularly defined in the appended claims.

In the accompanying drawing, which is intended merely to illustrate and not to limit my invention,

Fig. 1 is a plan view of my stone dress-

ing machine applied to a stone which is 55 being dressed.

Fig. 2 is a longitudinal sectional view on the line II—II of Fig. 1, the motor being shown in elevation for the purpose of simplicity;

Fig. 3 is a transverse sectional view taken on the line III—III of Fig. 2 and showing the controlling mechanism for the disk advancing means;

Fig. 4 illustrates the belt drive from the 65 motor shaft to the disk shaft;

Fig. 5 is a plan view of an adjustable supporting plate for the machine;

Fig. 6 is a plan view of the machine (with the motor removed) supported by a 70 modified form of supporting plate; and

Fig. 7 shows, in reduced scale, a stone in which both the grooves and the fours have been cut by my machine.

Referring particularly to Figs. 1 and 2, 75 the supporting plate 10 is pivotally supported at one end by the pedestal 11 which is located at the center of the stone to be dressed. The other and outer end of the plate 10 is supported by means of the leg 80 12 which rests upon the outer edge 13 of the stone. This arrangement permits of the radial adjustment of the supporting plate, and the parts carried thereby, about the center of the stone as an axis.

Mounted upon the plate 10 adjacent its outer end is a frame 14 upon the top of which the electric or other motor 15 is supported by the thrust bearing 16. As will be described presently, this motor, in its 90 normal operation, is adapted to oscillate back and forth in a horizontal plane upon the bearing 16. The vertical spindle 17, which is supported by the frame 14, is located at the axis of oscillation of the motor 95 and is oscillated thereby. The motor also imparts to the shaft 17 an intermittent downward or advancing movement to which I shall refer more in detail hereinafter. At its lower end the shaft 17 carries the 100 support 18 for the sleeve 19' within which is the shaft 19 which carries at its outer end cutting wheels or disks 20 which may be of any desired number and dimensions and spaced at any desired distance apart. These 105 disks may be of any suitable abrasive material, such as emery, carborundum, etc.

The shaft 19 is driven from the motor

shaft 21 by any suitable means, such, for example, as the belt 22 interposed between the drive pulley 23 mounted on the motor shaft 21 and the driven pulley 24 mounted upon the disk shaft 19. Thus the motor 15 spins the disks 20 about their own axis and, through the shaft 17, causes them to partake of a horizontal oscillatory or swinging movement, and an intermittent, downward or disk-advancing movement. The result is that when properly positioned and adjusted my machine, or more properly the disks 20 of my machine, will automatically cut in the stone arcuate grooves of the desired character and depth. By properly adjusting the axes about which the disks 20 spin and oscillate, it is apparent that the character of the grooves may be widely varied. That is, they may be made of equal depth throughout, or they may be made of unequal depth, with the greatest depth either at their inner extremity or at their outer extremity. Again, they may be cut perpendicular to the surface of the stone, or at any other desired angle thereto.

Before describing the method of operation of my machine any more in detail, I shall now describe the means which I employ for imparting to the shaft 17 and thus to the disk shaft 19 and disks 20, the horizontal or oscillatory movement and the intermittent downward or disk-advancing movement to which I have referred above.

As above stated, the horizontal oscillatory movement is imparted to the shaft 17 by the motor 15 which, itself, oscillates upon the bearing 16, and to the base 25 of which the shaft 17 is splined as indicated at 26. The motor may be oscillated or, more accurately speaking, may be caused to oscillate itself in the following manner. The forward end of the motor shaft 21 is provided with a worm 27 which engages with the worm wheel 28 mounted upon the shaft 29 which is supported by the bracket 30 secured to the motor casing. At its lower end the shaft 29 carries the gear 31 which meshes with and drives the gear 32 which in turn drives the slotted crank 33. The worm and gears are so proportioned as to drive the crank 33 at the desired speed relative to the speed of the motor shaft, and, obviously, any other suitably proportioned power transmitting mechanism may be substituted for the gearing above described.

The slot 34 in the crank 33 receives the pin 35 which is carried at the outer end of the link 36, the inner end of which is pivoted at 37 to the stationary frame 14. The pin 35 may be retained at any desired position within the slot 34 by means of the nut 35^a. Thus it is apparent that the rotation of the crank 33, in cooperation with the pivoted link 36, will oscillate the motor up on its thrust bearing 16. The extent or am-

plitude of this oscillation of the motor and the resulting oscillation of the shafts 17 and 19 and the disks 20 depends upon the position of the pin 35 in the slot 34. The center line of the oscillations may be adjusted with reference to the center line of the machine by lengthening or shortening the link 36 by means of the turn buckle 38.

The means which I prefer to employ for imparting the intermittent downward or disk-advancing movement to the shaft 17 and to the shaft 19 and disks 20 which are supported by the shaft 17, are as follows: Surrounding the major portion of the shaft 17 is the hollow shaft 39, the exterior surface of which is screw-threaded and is in engagement with the female thread portion 40 of the stationary frame 14. Relative longitudinal movement between the shafts 17 and 39 is prevented by some such means as the abutment 41 of support 18, and the nut 42 which takes on shaft 17 adjacent the upper end of shaft 39. Between the abutment 41 and the lower end of shaft 39 and between the nut 42 and the upper end of shaft 39, I preferably place thrust bearings as shown at 43 and 44 to facilitate relatively rotary movement between the shafts 17 and 39. It is apparent that the rotation of the threaded shaft 39 in the proper direction within the female threaded portion 40 of the stationary frame will result in the downward movement of the shaft 39 and of the parts carried thereby, namely, the shaft 17 and the disk-carrying shaft 19 and disks 20. The belt tightening device 23^a is provided to compensate for the vertical movement of the driven pulley 24 of shaft 19 relatively to the drive pulley 23 of motor shaft 21.

I effect the above referred-to rotation of the shaft 39 in the following manner: The collar 45 is secured to the shaft 17, adjacent its upper end, by some such means as a set screw 46 (Figs. 2 and 3). This collar is provided with a lug 47. Loosely mounted on the shaft 17 adjacent the collar 45 is a pawl-arm 48 which carries at its outer end a pawl 49, and at its inner end two spaced lugs 50, 51, each provided with an adjustment screw 52, 53, and a lock nut. The pawl 49 cooperates with the ratchet 54 which is secured to or is integral with the shaft 39. The lug 47, as it oscillates with the shaft 17, first strikes the screw 52 of lug 50, swinging the arm 48 in a counter-clockwise direction (Fig. 3) and retracting the pawl with relation to the ratchet, and then strikes the screw 53 of lug 51, swinging the arm 48 in a clockwise direction and advancing the pawl 49 and causing it to rotate the ratchet 54 and shaft 39. This intermittent rotation of the shaft 39 results, of course, in the intermittent downward or disk-advancing movement of the shafts 39, 130

17 and 19 and the disks 20. The ultimate result is that the disks cut into the stone a little deeper at each oscillation. The depths which the disks are advanced at each oscillation depend upon the number of teeth the ratchet 54 is advanced at each oscillation and may be regulated by adjustment screws 52, 53.

In order that the grooves cut by the disks 19 may be of the desired depth throughout their length I have so arranged the lugs 47, 50 and 51 that the lug 47 does not contact with the screw 53 of lug 51 until the disks have traveled out beyond the periphery of 15 the stone. For example, Figs. 1 and 3 represent the disks and associated parts at the inner limit of their travel. The lug 47 (Fig. 3) has just contacted with the screw 52 and pushed it and the lug 50 and arm 48 in a 20 counter-clockwise direction, retracting the pawl 49 a number of teeth, depending upon the adjustment of screws 52, 53. The disks and their associated parts are now ready to start on their outward travel. As they move 25 outwardly the lug 47 moves away from the lug 50 but does not strike the lug 51, or its screw 53, until after the disks 20 have passed off of the stone. It then strikes the lug 51 (or screw 53) and advances the pawl, 30 ratchet, etc., the predetermined amount.

In conjunction with the mechanism which I have just described for advancing the disks, I provide means for stopping the machine automatically after the disks have been advanced a predetermined total amount, or in other words, after the particular series of grooves being cut have been cut to the predetermined depth. These means include an adjustable clip 55 which 35 may be secured by a set screw at any desired point upon the periphery of the ratchet wheel 54. At each oscillation of the machine this clip is advanced with the ratchet toward the lever arm 56 of the electric switch 57 which controls the motor circuit 40 preferably through a magnetically retained starting box lever, or the like. Finally the pin 58 of the clip strikes the lever arm 56 of the switch, opening the switch and 45 stopping the motor. The amount of advance of the ratchet and the disks 20 which will take place before this stoppage occurs, depends, of course, upon the original setting of the clip 55 on the ratchet wheel; 50 that is, the distance originally existing between the clip and the switch. As herein shown, the pin 58 of the clip 55 is in the form of a vertically extending rod which is so arranged that the switch lever arm will lie in its path even though the ratchet 54 is considerably depressed. Of course the clip 55 may be so arranged that it will open the switch 57 only as it reaches it the second time, if a deeper cut is desired than will

result from one complete revolution of the 65 ratchet wheel 54.

The method of operation of my machine is as follows: The machine is placed upon the stone to be dressed, and cutting disks of the desired number, size and spacing are 70 secured to the shaft 19. The ratchet 54 is turned manually to place the disks at the proper level for the initial cut. The screws 52, 53 are adjusted for the desired disk-advance for each oscillation, and the clip 75 55 is set for the desired total depth of cut. The machine is then started by closing the motor circuit and the disks are caused by the motor to spin, to oscillate and to advance in accordance with the requirements of the particular job. When the disks have advanced the required amount, that is, when the grooves have been cut to the required depth, the pin 58 of clip 55 strikes the lever arm 56, opens the switch 57 and stops the 80 motor. The operator then adjusts the plate 10 and the parts supported by it upon the stone so that the disks are in the proper position to cut another series of grooves, the ratchet wheel 54 being retracted to place the disks again at their proper starting level, and the motor is again started. The above described operation is repeated until the 85 entire surface of the stone is dressed.

In addition to cutting the grooves or 90 "cracks" in the stone, as above described, my machine may be utilized also to cut the larger and more widely separated grooves known as the "fours," by using suitable cutting disks and properly adjusting the machine to provide for grooves of the desired length and depth. In Fig. 7 I have shown a stone in which both the grooves or 95 "cracks" C and the "fours" F have been cut by my machine.

If it is desired to provide for the adjustment of the operative parts of my machine toward and from the center of the stone, this may be done by substituting for the supporting plate 10 of Fig. 1 a slotted supporting 100 plate such as is shown at 10^a of Fig. 5. The slots 10^b of this plate are adapted to receive the screws or bolts by which the frame 14 is secured to the plate and to permit the adjustment of the frame and all of the parts 105 carried thereby. The slot 10^c provides clearance for the shaft 17 as the frame 14 is adjusted.

Instead of employing a plate such as 10 or 10^a, adapted to be supported by the stone 110 to be dressed, a plate such as 10^d (Fig. 6) may be used. This plate is supported in any suitable manner (as by legs, not shown) independently of the stone. When it is used the stone may be supported upon a turn-table or otherwise arranged so that it may be rotated with reference to the dressing machine, at the completion of each series of 115 120 125

cuts, the frame 14 remaining stationary. In other respects the machine shown in Fig. 6 is the same as that described above.

The advantages of my invention, as above described, will be apparent to those skilled in the art. They include the production of more regular, keener edges and more efficient grooves than has been possible heretofore, coupled with the reduction of the labor cost to a practically negligible amount. In the use of my invention only enough of the stone is cut out to form the desired grooves, while when the grooves are chiseled, as has been customary heretofore, more of the stone is cracked out than is necessary to produce the cutting edges. My invention therefore not only produces more efficient grooves, but in doing so also economizes on stone.

20 The only labor required to dress stones when my machines are used is that of a comparatively unskilled workman who resets the machine each time it automatically stops upon the completion of a series of grooves, and this workman can be doing other things between times. Also the length of time required to dress a stone with the use of my machine is very much less than that consumed in the old manual process, as will readily appear. This is of particular importance, not only because of its saving in labor, but also because usually a mill, representing a large investment, remains idle while its stones are being dressed.

35 Many changes may be made in the machine herein described without departing from the spirit of my invention.

The machine herein disclosed and the modifications herein suggested are not intended in any way to include all of the embodiments of my invention as defined in the appended claims, but are intended merely as illustrative embodiments of that invention.

45 In certain of the claims I have referred to the oscillation of the cutting disks as being "substantially parallel" to the surface of the stone, and to the advance of those disks as being "substantially perpendicular" to that surface. Of course, if the grooves are cut of uniform depth throughout their length the oscillation of the disks will have to be parallel to the stone surface, and if the grooves are cut perpendicularly the advance 50 of the disks will have to be perpendicular to that surface. But since I contemplate using my machine also to cut grooves of greater depth at one end than at the other, and grooves which are not exactly perpendicular 55 to the stone surface, I have used the expressions "substantially parallel" and "substantially perpendicular" and intend these expressions to cover the operation of my machine irrespective of the particular character 60 of groove it may be adjusted to cut.

It should be understood, also, that in referring to my machine as a "stone dressing machine" and to the object it is adapted to dress as a "stone," I do not use the word stone in its ordinary literal sense but intend to cover thereby all milling or similar members which require dressing whether they be made of stone, metal, or other material. Furthermore, in using the term "oscillating" as applied to the to-and-fro movement of the disks I do not intend to limit myself to a movement in the arc of a circle since, as above noted, this movement may be in any desired curve or in a straight line in any desired direction.

The terms and expressions which I have employed are used as terms of description and not of limitation, and I have no intention, in the use of such terms and expressions, of excluding any mechanical equivalents of the features shown and described, or portions thereof, but recognize that various structural modifications are possible within the scope of the invention claimed.

What I claim is:

1. In a stone dressing machine, a driving shaft, a disk shaft disposed substantially parallel to the stone to be dressed and having one or more cutting disks mounted thereon, power operated means for rotating said disk shaft, means operated from said driving shaft for oscillating said disk shaft in a plane substantially parallel to the surface of said stone, and means also operated by said driving shaft for advancing said disk shaft in a direction substantially perpendicular to said surface to increase the depth of cut of said disks.

2. In a stone dressing machine, a driving shaft, a driven shaft, one or more cutting disks mounted upon said driven shaft and driven thereby and adapted to contact with the surface of a stone to cut the same, and means operated from said driving shaft for oscillating said driven shaft in a direction substantially parallel to the surface of said stone and for advancing said driven shaft in a direction substantially perpendicular to said surface to increase the depth of cut of said disks.

3. In a stone dressing machine, a driving shaft, a driven shaft, one or more cutting disks mounted upon said driven shaft and driven thereby and adapted to contact with the surface of a stone to cut the same, means operated from said driving shaft for oscillating said driven shaft in a direction substantially parallel to the surface of said stone, and means operated from said driving shaft and adapted to advance said driven shaft at each oscillation thereof, in a direction substantially perpendicular to said surface, to increase the depth of cut of said disks.

4. In a stone dressing machine, a driving

- shaft, a driven shaft, one or more cutting disks mounted upon said driven shaft and driven thereby and adapted to contact with the surface of a stone to cut the same, means 5 operated from said driving shaft for oscillating said driven shaft in a direction substantially parallel to the surface of said stone, means for adjusting the amplitude of said oscillations, and means operable from 10 said driving shaft and adapted to advance said driven shaft at each oscillation thereof in a direction substantially perpendicular to said surface to increase the depth of cut of said disks.
- 15 5. In a stone dressing machine, a power operated shaft, one or more cutting disks mounted thereon and driven thereby and adapted to contact with the surface of a stone to cut the same, means for automatically 20 oscillating said shaft and at each oscillation thereof advancing it in a direction substantially perpendicular to said surface to increase the depth of cut of said disks, and adjustment means for predetermining 25 the distance said shaft is to be so advanced at each oscillation.
6. In a stone dressing machine, a power operated shaft, one or more cutting disks mounted thereon and driven thereby and 30 adapted to contact with the surface of a stone to cut the same, means for automatically oscillating said shaft and at each oscillation thereof advancing it in a direction substantially perpendicular to said surface to 35 increase the depth of cut of said disks, and means adapted automatically to stop said machine when said shaft has been advanced a predetermined total distance.
7. In a stone dressing machine, a power 40 operated shaft, one or more cutting disks mounted thereon and driven thereby and adapted to contact with the surface of a stone to cut the same, means for automatically oscillating said shaft in a plane sub- 45 stantially parallel to the surface of said stone, and means to adjust the amplitude of said oscillations to conform to the size of the stone being dressed.
8. In a stone dressing machine, a power 50 operated shaft, one or more cutting disks mounted thereon and driven thereby and adapted to contact with the surface of a stone to cut the same, means for automatically oscillating said shaft in a plane sub- 55 stantially parallel to the surface of said stone, and means for adjusting the center line of said oscillations with respect to the center line of said machine.
9. In a stone dressing machine, a power 60 operated shaft, one or more cutting disks mounted thereon and driven thereby and adapted to contact with the surface of a stone to cut the same, means for automatically oscillating said shaft in a plane sub- 65 stantially parallel to the surface of said
- stone, means to adjust the amplitude of said oscillations to conform to the size of the stone being dressed, and means for adjusting the center line of said oscillations with respect to the center line of said machine. 70
10. In a stone dressing machine, a power operated shaft, one or more cutting disks mounted thereon and driven thereby and adapted to contact with the surface of a stone to cut the same, means for automatically oscillating said shaft and at each oscillation thereof advancing it in a direction substantially perpendicular to said surface to increase the depth of cut of said disks, means adapted automatically to stop said machine when said shaft has been advanced a predetermined total distance, and adjustment means for predetermining said total distance. 75
11. In a stone dressing machine, a power operated shaft, one or more cutting disks mounted thereon and driven thereby and adapted to contact with the surface of a stone to cut the same, means for automatically oscillating said shaft and at each oscillation thereof advancing it in a direction substantially perpendicular to said surface to increase the depth of cut of said disks, adjustment means for predetermining the distance said shaft is to be so advanced at each oscillation, and means adapted automatically to stop said machine when said shaft has been advanced a predetermined total distance. 80
12. In a stone dressing machine, a power operated shaft, one or more cutting disks mounted thereon and driven thereby and adapted to contact with the surface of a stone to cut the same, means for automatically oscillating said shaft and at each oscillation thereof advancing it in a direction substantially perpendicular to said surface to increase the depth of cut of said disks, adjustment means for predetermining the distance said shaft is to be so advanced at each oscillation, and means adapted automatically to stop said machine when said shaft has been advanced a predetermined total distance, and adjustment means for predetermining said total distance. 85
13. In a stone dressing machine, a power driven and oscillated shaft adapted to carry and drive stone cutting disks, a support for said shaft provided with a pawl and ratchet mechanism, and means partaking of the oscillatory movement of said shaft for advancing said pawl and ratchet mechanism to impart an advancing movement to said shaft supporting means and said shaft, at each oscillation thereof. 90
14. In a stone dressing machine, a frame, a power driven and oscillated shaft adapted to carry and drive one or more stone cutting disks, a support for said shaft in screw-threaded engagement with said frame and provided with a ratchet, a pawl, and means 125
- 130

partaking of the oscillatory movement of said shaft for oscillating said pawl and thereby imparting to said ratchet and support a rotary movement, at each oscillation 5 of said shaft, said screw threaded engagement between said support and frame serving to translate said rotary movement into a shaft advancing movement in a direction substantially perpendicular to the surface of the stone being dressed.

15. In a stone dressing machine, a frame, a power driven and oscillated shaft adapted to carry and drive one or more stone cutting disks, a support for said shaft in screw-threaded engagement with said frame and provided with a ratchet, a pawl, means partaking of the oscillatory movement of said shaft for oscillating said pawl and thereby imparting to said ratchet and support a rotary movement, at each oscillation of said shaft, said screw threaded engagement between said support and frame serving to

translate said rotary movement into a shaft advancing movement in a direction substantially perpendicular to the surface of the 25 stone being dressed, and adjustment means for predetermining the extent to which said pawl is oscillated by said first mentioned means.

16. In a stone dressing machine, a power 30 driven and oscillated shaft adapted to carry and drive one or more stone cutting disks, a support for said shaft provided with a pawl and ratchet mechanism, means partaking of the oscillatory movement of said shaft for 35 advancing said pawl and ratchet mechanism to impart an advancing movement to said shaft supporting means and said shaft, at each oscillation thereof, and means operated by said pawl and ratchet mechanism and 40 adapted to stop said machine when said pawl and ratchet mechanism has been advanced a predetermined total distance.

LEONARD DOTZER.
